UNITED STATES PATENT OFFICE

141,359

DESIGN FOR A DESK

Emil B. Carlson and Clyde G. Morgan,
Chicago, Ill.

Application March 26, 1945, Serial No. 118,722

Term of patent 14 years

(Cl. D33—7)

To all whom it may concern:

Be it known that we, Emil B. Carlson and Clyde G. Morgan, citizens of the United States and residents of Chicago, in the county of Cook and State of Illinois, have invented a new, original, and ornamental Design for Desk, of which the following is a specification, reference being had to the accompanying drawing, forming part thereof.

Fig. 1 is a front perspective view of a desk showing our new design.

Fig. 2 is a rear perspective view of the desk shown in Fig. 1.

I claim:

The ornamental design for a desk, as shown.

EMIL B. CARLSON.

CLYDE G. MORGAN.
